THREAD-HANDLING DEVICE

Carlyle Herbert Wainwright, Tom Leslie Mountain, and Frederick Edward Deans, Leicester, England, assignors to The Bentley Engineering Company Limited, Leicester, England, a British company

Application November 26, 1938, Serial No. 242,608
In Great Britain December 9, 1937

15 Claims. (Cl. 242—131)

This invention is for improvements in or relating to thread-handling devices which are applicable for use in connection with knitting machines, but which are also applicable for use in other machines in which a number of different threads have to be dealt with.

It is customary, in the knitting industry, to make provision for the supply to the needles of a knitting machine, of one or more threads of a number of different threads, and accordingly the machine is equipped with handling devices for these threads including thread guides, thread tension devices, and holders for the bobbins containing supplies of the threads.

15 It is an object of the present invention to provide an assembly of thread-handling devices including a number of bobbin holders, or of thread tension devices, or of thread guides, or a number of any two or all of such elements, which 20 assembly shall have the characteristic that any desired number of said elements can readily be assembled or the number of said elements can be increased or diminished with rapidity and facility to suit the requirements of work to be 25 produced by the machine at any time.

Other objects of the invention are to provide an assembly of thread-handling devices which shall be pleasing in appearance, convenient in use, and component parts of which shall be inexpensive to manufacture; and generally to improve devices of such character.

30 A feature of the present invention is a built-up assembly of thread-handling devices comprising in combination a plurality of separate members each adapted to support at least one thread-handling device, and means for attaching or for enabling the attachment of each to a companion member to form a series of said members. The purpose of such an arrangement is to permit the 35 device-supporting capacity of the assembly readily to be varied, by the removal from said series of one or more of said members, or by the addition to the series of one or more similar members.

40 An assembly of the kind defined in the preceding paragraph may comprise a series of bobbin holders, each of which is of elongated formation and has at one end provision for the support of a bobbin and at the other end provision for the 45 attachment thereto of an end of a companion bobbin holder. Conveniently, the support for the bobbin on the bobbin holder is in the form of a peg which is utilised as part of the means for attaching one bobbin holder to another.

50 In a modification the invention comprises an

assembly of thread-handling devices in which each of the members aforesaid is a support for a thread tension device or for a thread-guiding device or for both such devices, which support has at one part a tube-like formation into which a part of a companion member can be introduced to attach the two members together.

5 The foregoing and other details of the invention will now be described with the aid of the accompanying drawings which illustrate some 10 preferred forms of the invention and in which—

Figure 1 is an elevation of one form of the invention providing a plurality of bobbin supports;

Figure 2 is a plan of the bobbin supports and 15 associated thread guides shown in Figure 1;

Figure 3 is a section on the line 3—3 of Figure 2, looking in the direction of the arrows;

Figure 4 is a section on the line 4—4 of Figure 2, looking in the direction of the arrows;

Figure 5 is an elevation similar to Figure 1 of a small portion of a modification of the assembly according to the present invention showing a built up series of thread tensioning devices, and

25 Figure 6 is a section on the line 6—6 of Figure 5, looking in the direction of the arrows.

Like reference numerals indicate like parts in the several figures of the drawings.

In the first modification of the invention illustrated in Figures 1 to 6, the construction of thread-handling devices consists of a plurality of sets of these devices each comprising a bobbin stand, a thread tensioning device and yarn guides. All these devices are supported upon a vertically disposed rod 10 which is preferably tubular and will hereinafter be referred to as the vertical tube. The vertical tube is supported near its lower end by a bracket 11 fixed to a convenient part of the knitting machine and extends into a second tube 12 which is also fixed to the bracket. The vertical tube 10 is free to rotate and to move endwise in the second tube and a clamp 13 or any other preferred means is provided to lock the vertical tube in any desired position of adjustment. By this arrangement the vertical tube and all the parts supported by it can be raised or lowered and swung about the axis of the tube either for adjusting purposes or to give access to some part of the machine without disturbing the assembly of the thread-handling devices carried by it.

The bobbin stands or holders are supported by a bracket 14 secured to the vertical tube 10, which bracket at its outer end has two arms 15

and 16 disposed at an angle of about 60° in relation to each other. The stand for each bobbin comprises a plate 17 somewhat in the shape of a dumb-bell when regarded in plan, each such plate having circular end portions joined by a straight parallel-sided portion. Each of the plates 17 is of dished formation, the edge of the plate being downturned through slightly less than a right-angle to provide a rounded upper margin to the plate. For attaching these plates to each other in series, each plate has in each circular end a hole for the reception of a bolt 18 which in this case is extended above the plates to constitute the usual pegs or rods over which the bobbins are threaded. The lower portions of each such bolts or pegs are screwthreaded for the reception of nuts 19 by which the overlying ends of adjacent plates are secured together.

In the illustrated example of the invention the plates are bolted together end to end to form two lines of bobbin stands arranged in parallel rows and the two lines of plates are joined at each end by another similar plate also bolted to its companion, thus forming a parallelogram.

This parallelogram is bolted to the ends of the two arms 15 and 16 by means of a bolt or peg 18, and as the bolt holes at the end and the junction of the two arms 15 and 16 are equidistant from one another, and the distance between a pair of these holes is the same as that between the two holes in each of the plates, the parallelogram of plates can be bolted to the bracket by the same bolts which secure together parts of the said parallelogram.

Between the overlying ends of the pairs of plates secured by a bolt such as 18 are inserted washer-like distance pieces 20. Each of these distance pieces is in the form of a disc with a rounded edge and a central hole, and may be formed of cast material, for example cast iron. Each circular plate of each of the distance pieces is recessed somewhat at its central portion as shown at 21 so as to form a flat annular bearing surface at the margin of the piece on each flat face. The overlying ends of pairs of plates and interposed washers are secured tightly together by means of the nuts 19, and similarly in positions where the overlying plates are secured to the junction and extremities of the bracket arms 15 and 16 distance pieces will be utilised between the lowermost plate and the bracket arms, all the parts being similarly clamped between nuts 19.

From the foregoing description it will be appreciated that the bobbin-carrying capacity of the structure can be readily varied by the addition of further plates to the structure or by the removal of plates therefrom.

At the upper end of the vertical tube 10 (i. e. 60 above the assembly of bobbin stands) there is a supporting bracket 22 for thread tensioning devices and thread guides. In the form illustrated in Figures 1 to 6 the bracket 22 is not of the built up kind but comprises a single bar of angle 65 section attached to a bracket 123 at the top of the vertical tube.

Bolted to and extending at right-angles to the length of the bar 22 are arms 23 the outer ends of which terminate above the bobbin pegs 18 of 70 the two parallel rows of bobbin stands and at the outer end of each such arm 23 there is a pot-eye or thread guide 24 of well known form. Yarn 75 is led from a bobbin supported on a peg 18 through this pot-eye 24 and thence to other pot-eyes 25 and 26. Each superposed pair of pot-eyes

25 and 26 is secured in a plate 27 that is also bolted to the bar 22 and the bolt which secures the arm 23 and plates 27 for each bobbin stand also constitutes the spindle for a thread tensioning device. 5

Each tensioning device is of the well known cymbal type the thread receiving discs 28 of which are mounted on the bolt 29 and are pressed together by a spring 30 which surrounds the bolt and bears at one end upon one of the discs 10 and at the other end upon an adjoining nut 31 on the bolt.

The arms 23 are naturally of two different lengths, the shorter arm extending over what may be termed the inner line of bobbin stands, 15 and the longer arm over the outer line. The long and short arms are arranged in intercalated manner and each arm 23 is conveniently formed from relatively thin material which in cross-section is dished or of channel formation 20 to give the necessary rigidity to the arms.

It is possible with the arrangement described for the yarns from two bobbins, one in a front line and the other in a rear line, to be led to the same tensioning device as shown at the left-hand end of Figure 2. Alternatively, the yarn from each bobbin may pass through its own tensioning device, there being the same number of such devices as there are bobbin pegs as will be clearly seen from the drawings. 30

If an additional yarn is required as for example a splicing yarn, additional plates similar to 17, and indicated in Figure 2 by the reference numeral 117, may be employed and these extend rearwardly, that is to say, in a direction 35 towards the plate 22.

For such an additional bobbin stand the pot-eyes 25 and 26 and their supporting plates 27 will be somewhat modified in form and will be constructed as shown in Figure 3. In this case the supporting plate is indicated by the reference numeral 127 and the pot-eyes by the reference numerals 125 and 126 and the run of the yarn between these pot-eyes is such as to lead the yarn between tensioning devices, including discs 28, as 40 before. 45

A second preferred embodiment of the invention is illustrated in Figures 7 and 8 which show the application of the invention to the formation 50 of a built up carrier for thread tensioning devices.

These devices comprise a plurality of units and one unit is secured to a bracket similar to 123 of the previous construction, for instance by bolts 124 also in conformity with the manner in which 55 the angle iron bracket 22 is secured in the previous example.

Each unit comprises an elongated plate which is bent along its length to form a horizontal portion 34 and a vertical portion 35. Near each end of this plate there extends from the top of the vertical portion a lug which is bent over into portions 36 and 37, the former of which is horizontal and the latter of which extends vertically downward but which does not quite reach the horizontal portion 34. In cross-section each end of the plate thus represents an incomplete rectangular tube, one of which, however, is smaller than the other in cross-section so that the tubular portion 70 of smaller size can enter the adjacent end of a tubular portion of larger size in a companion unit next to it, thereby attaching the two units together. 65

The vertical portion 35 of each unit has up- 75

standing ears 135 at the upper end of each of which there is a hole for the reception of a thread-guiding pot-eye 25 as in the previous example; and a companion pot-eye 26 is inserted in a hole formed in the overlapping horizontal portions 34 of adjacent unit ends where one unit end has been passed over a companion end of the next unit. Fixed also in the vertical portion 35 of each unit in a manner similar to that already described are bolts 29 carrying thread tensioning discs 28, springs 30 and nuts 31 as already described.

Thus in this case it will be seen that the number of units to be employed in building up the required number of thread tensioning devices with their associated thread guides can readily be varied since the tubular formation at the ends of these units facilitates the removal of one or more units from the assembly or the addition thereto of one or more units.

20 We claim:

1. In or for a knitting or other machine in which a number of threads is to be handled, a built-up assembly of thread-handling devices comprising the combination of a plurality of separate similar supporting members each serving to support at least one thread-handling device, thread-handling devices on the supporting members, each disposed so as to feed one of a number of threads allocated between them, the said supporting members being arranged in a series end to end, means to attach a member of such series to a fixed stand or other fixed support and, for other members of said series, means to attach the end of each member to the adjacent end of the next member of the series and so on whereby the said other members nearer the fixed support serve to support members of the series further from the fixed support.

2. An assembly according to claim 1 wherein each of said members is of elongated formation having at one end provision for supporting a thread-handling device and at the other end provision for attachment thereto of an adjacent end of a companion member.

45 3. An assembly according to claim 1 wherein each of said members is of elongated formation and is combined with a peg situated at one end thereof for receiving a bobbin, the said peg also forming part at least of the means for attaching one member to an adjacent member.

4. An assembly according to claim 1 wherein each of said members affords a support for a bobbin holder and is of elongated formation having at one end provision for supporting said bobbin holder and at the other end provision for attachment thereto of an adjacent end of a companion member and in which each member seen in plan is of substantially dumb-bell form.

5. An assembly according to claim 1 wherein each of said members affords a support for a bobbin holder and is of elongated formation having at one end provision for supporting said bobbin

holder and at the other end provision for attachment thereto of an adjacent end of a companion member and in which each member is formed of sheet material dished in cross-section to afford requisite rigidity.

6. An assembly according to claim 1 wherein each of said members affords a support for a bobbin holder and is of elongation formation having at one end provision for supporting said bobbin holder and at the other end provision for attachment thereto of an adjacent end of a companion member and in which each member is formed of sheet material dished in cross-section to afford requisite rigidity combined with a spacing washer interposed between superposed members, for the purpose set forth.

7. An assembly according to claim 1 wherein each of said members comprises a support for a thread-tensioning device.

8. An assembly according to claim 1 in which each member comprises a support for a thread-guiding device.

9. An assembly according to claim 1 wherein each member comprises a support for a thread-tensioning device and for a thread-guiding device.

10. An assembly according to claim 1 in which each member has at one part a tube-like formation into which part of a companion member can be introduced in order to attach the two members together.

11. An assembly according to claim 1 in which each member has at one part a tube-like formation into which part of a companion member can be introduced in order to attach the two members together, and in which each member comprises a support for a thread-tensioning device.

12. An assembly according to claim 1 in which each member has at one part a tube-like formation into which part of a companion member can be introduced in order to attach the two members together, and in which each member comprises a support for a thread-guiding device.

13. An assembly according to claim 1 in which each member has at one part a tube-like formation into which part of a companion member can be introduced in order to attach the two members together, and in which each member comprises a support for a thread-tensioning device and for a thread-guiding device.

14. An assembly according to claim 1 comprising thread-tensioning devices carried by said member and comprising a spindle and thread-tensioning discs threaded thereon in combination with thread-guiding eyes carried in separate supports which are also secured to said members.

15. An assembly according to claim 1 comprising thread-tensioning devices in which the latter are secured in upstanding portions of individual members of the assembly.
